SUCTION CLEANER

George P. Daiger, Canton, Ohio, assignor to The
Hoover Company, North Canton, Ohio, a cor-
poration of Ohio

Application September 23, 1937, Serial No. 165,282

10 Claims. (Cl. 15—16)

This invention relates to improvements in suction cleaners and more particularly to automatic nozzle adjusting mechanisms for suction cleaners operating to adjust the height of the nozzle properly to the particular floor covering to be cleaned without any effort on the part of the operator.

Nozzle height adjusting mechanisms of the automatic type have been fully disclosed in two earlier applications, to wit, Serial No. 96,222 filed 10 August 15, 1936, and Serial No. 102,883 filed September 28, 1936, now Patent No. 2,146,006. But in each of these automatic nozzle adjusting mechanisms the operator is required to depress a foot pedal in order to initiate the adjusting 15 operation and hence they cannot properly be considered as wholly or fully automatic in operation.

Hence, the object of the present invention is primarily that of converting the heretofore disclosed 20 partially automatic or "semi-automatic" type of nozzle height adjusting mechanism into a fully automatic mechanism by the application of a suitable power unit which will supply the force, otherwise exerted by the operator in the act of depressing the foot actuated operating 25 lever, but with the definite advantage that this power unit functions automatically whenever the cleaner is put into operation.

Moreover, since the adjusting mechanism per 30 se has already been fully disclosed as previously mentioned, the present disclosure is directed primarily to the application of the power unit to an already perfected device, although it should be understood that the present invention also 35 contemplates the possibility of eliminating the foot operation entirely, thus making the mechanism wholly automatic in its operation, although recognizing the fact that it would be perfectly practical to combine foot operation and the full 40 automatic operation, with the idea that should the operator neglect to make the adjustment, the automatic power unit would then respond and perform the adjusting operation notwithstanding. Then again, it is conceivable that suction 45 cleaners might preferably be manufactured with foot-operated nozzle adjusting mechanisms as standard equipment with the full-automatic feature to be added at the time of purchase or later should the purchaser desire the added convenience offered thereby at a slightly increased cost. In other words, the auxiliary power unit may be considered either as an attachment or as an 50 integral part of a fully automatic system.

A preferred embodiment of the invention is

disclosed in the accompanying drawings in which:

Figure 1 is a general view in side elevation of a suction cleaner of standard design, with portions broken away and shown in vertical section as taken on line 1—1 of Figure 2.

Figure 2 is a bottom plan view of the major portion of the suction cleaner body showing the nozzle height adjusting mechanism.

Figure 3 is a view in side elevation corresponding generally to that of Figure 1, but showing the nozzle height adjusting mechanism from the opposite side of the cleaner.

Figure 4 is an enlarged detailed view in vertical section as taken on line 4—4 of Figure 2 and 15 showing the nozzle height adjustment mechanism in the position occupied by the various parts during the interval that force is being applied by the auxiliary power unit.

Figure 5 is a perspective view of the primary 20 operation lever through which the force is applied to the nozzle adjusting mechanism by the power unit.

Figure 6 is a wiring diagram showing the location of the electrically actuated power unit in the 25 electrical circuit of the suction cleaner.

Figure 7 is an enlarged detailed view showing a modified application of the auxiliary power unit including a centrifugally actuated switch for controlling a solenoid.

Figure 8 is a detail view of the centrifugal switch as it appears in top plan view with the top of the switch housing removed as on line 8—8 of Figure 7.

Figure 9 is a view of the solenoid circuit switch 35 as taken on line 9—9 of Figure 7.

Figures 10 and 11 are wiring diagrams showing alternative locations for the solenoid in the electrical circuit of the cleaner.

Referring to the cleaner in its general aspects, 40 the same comprises a main casing 1, having a nozzle portion 2, extending transversely of its forward end and having the form of an elongated chamber with a downwardly facing mouth. The casing extends rearwardly from the nozzle portion 45 50 55 60 65 70 75 80 85 90 95 100 105 110 115 120 125 130 135 140 145 150 155 160 165 170 175 180 185 190 195 200 205 210 215 220 225 230 235 centrally of its bottom wall and concentric with the vertical axis of the fan and its driving motor. Extending forwardly from the fan eye 5a is a passage communicating with the interior of the nozzle 2, said passage being closed at its bottom by a removable plate 9.

Within the nozzle chamber and immediately above the suction mouth 10 is located a rotating agitator 11, consisting of a cylindric shell having brush elements 11a, 11a, arranged lengthwise thereof and helically arranged beater elements 11b, 11b. A drive belt 12 for the agitator is enclosed within the passage from the nozzle chamber to the fan chamber and extends from a pulley 13 carried at the lower end of the fan shaft to a pulley groove 11c midway between the ends of the agitator 11.

Again referring to the main casing 1, with its centrally disposed circular fan chamber 5, it will be noted that along the side edges are depending walls 1a, 1a and between these marginal walls and the sides of the fan chamber 5, are relatively deep cavities or spaces in which are located the wheeled support for the casing and the nozzle adjustment mechanism associated therewith.

Referring first to the supporting means for the cleaner, the same comprises a U-shaped chassis or carriage 15 carrying a pair of front wheels 16, 16 and a pair of rear wheels 17, 17, the latter having more the character of a two-wheeled caster beneath the rear end of the casing. The carriage or chassis 15 has pivotal connection with the casing just forwardly of the rear caster whereby the cleaner body is enabled to tilt about a horizontal axis.

Referring particularly to the form and mounting of the chassis or carriage 15, it has the form of a U-shaped casting disposed symmetrically beneath the cleaner casing 1 with its base portion 15a extending transversely beneath the rear of the casing and its two arms or branches 15b, 15b, extending forwardly just inwardly from the marginal side walls 1a, 1a. A pivot bolt 18, depending vertically from the bottom wall of the fan chamber 5 and passing through the center of the base portion 15a of the chassis frame 15 with a nut 18a mounted at its lower end supports a coil spring 19 to form a resilient pivotal or swivel connection between the cleaner casing 1 and the U-shaped wheeled chassis 15, which also have a knife edge contact permitting the body to tilt about a horizontal transverse axis.

Extending rearwardly from the base portion 15a of the chassis frame 15, is a supporting bracket 20 for an axle 21 on which are journalled the rear wheels or casters 17, 17. The forwardly extending arms 15b, 15b of the chassis frame 15 terminate in the form of downwardly and forwardly extending fork members 23, 23, supporting bearing pins 24, 24 at their lower end on which are journalled the front carrier wheels 16, 16.

Carried by the chassis 15 just rearwardly of and above the front wheels is an inverted U-shaped bail 25 which forms the lower extremity of the handle of the cleaner and projects through longitudinal slots in the top wall of the casing 1 with its ends pivotally mounted on bearing pins 26, 26 supported by the chassis frame 15. Thus the cleaner handle is carried by the chassis quite independently of the casing 1.

Associated with the handle bail 25 is a handle position control device which serves to restrain the handle from free swinging movement and defines its extreme positions as well as its inter-

mediate or working range. This device is already in common use and hence will not be described herein.

Referring now to the nozzle height adjusting mechanism, an adjustable casing supporting member is carried by the carriage 15 and consists of a somewhat irregular shaped ratchet lever 27 pivotally mounted on a bearing pin 28 carried at the forward end of one of the arms 15b shown in Figure 2. The upper end of the lever 27 has a slightly convex cam 27a having bearing contact with an inclined abutment plate 29 extending diagonally of the corner angle formed at the junction of the top wall of the casing 1 and the vertical rear wall of the nozzle chamber. 15

The ratchet lever 27 extends in a general downwardly and rearwardly inclined direction from its pivot pin 28 and as it approaches its rear end, spreads abruptly into a ratchet sector 30 having a curved outer edge in which are cut a series of ratchet teeth.

Also pivotally mounted on the same pin 28 that supports the ratchet lever 27 is another somewhat irregularly shaped lever 31 having the characteristics of a bell crank lever with a forwardly disposed arm 31a which extends in a downward direction and another arm 31b extending in a more rearwardly direction. 25

Referring to Figure 4, it will be noted that the depending arm 31a of the bell crank lever 31 lies just inside of the ratchet lever 27 and that its lower end supports a pivot pin 32 on which is journalled a pawl lever 33 extending rearwardly therefrom in a substantially horizontal direction. This pawl lever 33, the ratchet lever 27 and the bell crank lever 31 all oscillate in parallel vertical planes. However, the arm 31b of the bell crank lever 31 is offset inwardly from its other arm 31a, with the result that the two portions of the bell crank lever 31 actually straddle the pawl lever 33. The rear end of the pawl lever extends a short distance beyond the toothed edge of the ratchet sector 30 of the lever 27 and at its extreme end is provided a dog 33a projecting from its lower edge laterally at right angles to the toothed edge of the ratchet sector 30, with which it is adapted to have toothed connection. 40

Acting on the pivoted pawl lever 33 is a torsion spring 34 which is coiled around the pivot pin 32 with one end bearing against the lower edge of the lever 31 and the other end against the lower edge of the pawl lever 33, thus exerting a constant force upon the latter tending to swing it in a counterclockwise direction and the dog 33a at its free end toward the toothed edge of the ratchet sector 30. 55

Now, with the pawl dog 33a engaging the ratchet sector 30, it follows that the levers 27 and 31 become united and oscillate together and, if movement is imparted to the bell crank lever 31 while so connected with the ratchet lever 27, this movement will be transmitted to the casing 1 through the rolling contact between the cam member 27a of the ratchet lever 27 and the inclined abutment plate 29 on the casing 1. 65

The bell crank lever 31 is the primary moving member of this combination of inter-connected levers whereby the nozzle is raised and lowered by the rolling action of the cam 27a upon the inclined abutment plate 29, this adjusting movement being initiated by a pivoted rocking motion imparted to the bell crank lever 31 through an operating lever 35 supported intermediate its ends upon a transverse bearing pin 36 and 75

having an arm 37 extending forwardly and upwardly and terminating in a slotted or bifurcated end engaging a pin 38 carried at the rearmost extremity of the arm 31b of the bell crank lever 31. This operating lever 35 (shown in detail in Figure 5) has another arm 39 also extending forwardly from its bearing on the pin 36 but somewhat more horizontally than the first mentioned arm 37. The forward extremity of the lever arm 39 is shaped to form an upwardly facing U-shaped saddle 39a having a pin and slot connection with the lower end of a cylindric shaped movable core 40 of a solenoid or electromagnet 41 fixed to the underside of the top wall 15 of the cleaner casing 1 just rearwardly of the nozzle chamber and to one side of the passage connecting the nozzle chamber with the fan eye as clearly shown in Figure 2.

As arranged, the solenoid 41 is capable of actuating the lever 35 by exerting an upward pull at the forward end of its arm 39 when the solenoid is energized by electric current. As a type of electrical apparatus, a solenoid is too well known in the art to require further description, although presently its connection with the source of electrical energy will be pointed out and its function described in detail. In the meantime, it will be noted that the lever 35 also has a third arm 42 extending rearwardly beyond the pivot pin 36. This rearwardly extending arm 42 is considerably shorter than either of the forwardly extending lever arms 37 or 39 and U-shaped in cross section, it being apparent from Figure 5 that the lever 35 is preferably stamped from sheet metal so that the main portion thereof adjacent its pivotal mounting has the form of an upwardly facing channel while the forwardly extending arms 37 and 39 are extensions of the side walls of the main channel portion and which, incidentally, forms the somewhat shorter arm 42 just identified.

Also having pivotal mounting on the same bearing pin 36 with the lever 35, is a foot lever 43 extending rearwardly and positioned above and cradled by the shorter rearwardly extending lever arm 42 of the main operating lever 35. At the rearmost extremity of the foot lever 43 is a triangular shaped pedal 43a lying immediately outside the contour of the main casing and just to one side of the rearmost outlet connection 3 thereof as clearly shown in Figure 2. It should be observed at this point that the foot lever 43 has no positive connection with the main operating lever 35, being normally held in its normal elevated position by means of a torsion spring 44 acting to hold the same in contact with the underside of the chassis frame 15, as shown in Figure 4.

And finally, to place the entire nozzle adjusting mechanism under tension, a coiled spring 45 is supported vertically on end upon the chassis frame 15 and above the rearmost end of the operating lever 35. A rod 46 extends axially through the coiled spring 45 and downwardly through apertures in the chassis frame 15 and lever 43, and finally connected at its lower end with the end of the lever arm 42. This rod is connected with the spring 45 through a circular plate 45a which seats on top of the spring which thus exerts an upward force acting to rock the operating lever 35 on its bearing pin 36 in a counter-clockwise direction according to the showing of Fig. 4.

Referring once more to the solenoid 41, Figure 6 shows it connected in series with the field

coils of the motor 7, the conductors 47 leading to the solenoid from the motor being shown in Figures 1 and 2.

Inasmuch as the operation of the nozzle adjustment mechanism per se, is fully and elaborately pointed out in the previous disclosures mentioned, it is not considered necessary to repeat in detail the movement of each element constituting the adjusting mechanism. Consequently, it will be sufficient to point out that under normal operating conditions the nozzle height adjusting mechanism supports the casing 1 in a fixed position with the nozzle mouth raised a predetermined height above the carpet surface and the various parts of the adjusting mechanism at rest. The operating lever 35 in particular, assumes a generally horizontal position and the core 40 of the solenoid is lowered as it would be when the solenoid is demagnetized (Figure 1).

Now, if the cleaner is transferred from one carpet to another carpet having entirely different surface characteristics, the nozzle should be readjusted. This readjustment may be brought about by the operator pressing downwardly on the foot pedal 43, whereupon the entire forward portion of the casing drops until the nozzle mouth rests upon the upstanding carpet pile, thus establishing a horizontal plane above which the nozzle mouth is ultimately to be elevated. Hence upon the releasing of the foot pedal, the adjusting mechanism functions by spring pressure to elevate the nozzle a definite height above the carpet surface.

But now, as will be pointed out, the same operation may be performed by merely starting the motor of the cleaner in the usual manner.

Bearing in mind that the connection between the foot pedal 43 and the main operating lever 35 is a loose connection and furthermore, that the operating lever 35 has operative connection with the solenoid 41, it follows that the lever 35 will actuate the adjusting mechanism quite independently of the foot lever 43, whenever the solenoid is energized. Hence, ignoring entirely the foot lever 43 and which, as a matter of fact, might readily be removed entirely if desired, let it be pointed out that it is a characteristic of electric motors generally that considerably greater current supply is required on starting due to friction and the inertia of the moving parts. Therefore, it follows that upon starting the cleaner motor, the initial current supply is greatly increased for a period of several moments after the switch has been closed and until the motor has approached its normal speed. Hence, if this excessive starting current is impressed upon the solenoid, it will be momentarily energized, the core 40 retracted and the lever 35 shifted in the same direction and to the same extent as would result if the operator were to depress the foot lever 43. But the duration of the maximum starting current is only for a short period and as a consequence the weight of the cleaner body very soon overcomes the magnetic power exerted by the solenoid, whereupon the adjusting mechanism is free to complete the adjusting operation under spring tension and gravity, just as it does when the operator releases the foot pedal.

Thus it follows that the cleaner will be automatically adjusted to any surface to be cleaned merely by starting the motor, the only requisite being that the motor be stopped and started in transferring the cleaner from one type of carpet to another.

Figures 7 to 11 disclose slight modifications

of the electro-magnetically actuated nozzle height adjustment wherein the solenoid is located in a shunt circuit controlled by a centrifugal switch directly associated with the motor. This arrangement is somewhat more positive in its action in that the energizing of the electro-magnet is not dependent upon an increased starting current but rather upon the opening and closing of the solenoid circuit.

- 10 Insofar as the solenoid and its operative connection with the adjusting mechanism is concerned, the modified arrangement involves no particular departure. Thus Figures 10 and 11 show diagrammatically two possible alternative arrangements, one, wherein the solenoid circuit is shunted around a switch in one of the current supply lines to the motor (Figure 10); whereas in the other arrangement, the solenoid is shunted across the current supply lines with a switch in the solenoid circuit (Figure 11).

As shown in Figure 7, the centrifugal switch is preferably located in a housing 50 located at the upper end of the motor, similar in all respects to that shown in Figure 1. The armature shaft 51 of the motor terminates in this housing and fixed to the end of the armature shaft 51 is a circular disc or plate 52. On the upper face of this disc 52 is mounted a radially arranged switch member 53 with one end pivotally supported on a bracket 54 mounted adjacent the periphery of the disc with its inner free end positioned in alignment with the axis of the armature shaft 51.

Disposed approximately 120° from the switch member supporting bracket 54 and also adjacent the periphery of the disc 52 is another bracket 55 pivotally supporting one end of a flexible arm 56 carrying a weight 56a at its outer end, said arm 56 extending at right angles to the switch member 53. A light rod 57 anchored at one end to a short depending crank arm 53a at the pivoted end of the switch member 53, connects the latter with the flexible arm 56 intermediate its ends so that as the speed of the motor increases the weighted end of the arm 56 tends to move outwardly thus flexing the arm and in so doing transmits an endwise movement to the rod which in turn rocks the switch member 53 and in a direction to move its free end axially and outwardly toward the top of the housing 50.

Now, mounted within the housing 50 is a pair of conductor terminals 58 and 59 consisting of flat metal strips passing through the housing wall which necessarily would be of some insulating material. One of these terminal strips 58 is disposed radially against the inner face of the top wall of the housing 50, whereas the other strip 59 is placed at an angle of approximately 30° thereto with its inner end or portion bent to overlie the end of the other terminal strip 58 in spaced relation thereto, these strips having coacting contact points normally spaced apart to form an air gap.

65 In the arrangement shown in Figure 10, the conductors leading to the terminals 58 and 59 lead to the motor field circuit, and the switch 53 is shunted by the solenoid circuit. Thus when the motor is not in operation the switch is open and on starting the current passes through the shunt circuit and causes the solenoid to actuate the adjusting mechanism as before. However, when the motor increases its speed the arm 56 actuates the switch member 53 to close the switch and thus short circuits the solenoid, allowing the

adjusting operation to be completed by spring tension in the usual manner.

The arrangement shown in Figure 11 functions in much the same way, except that the centrifugal switch, being located in the shunt circuit is normally closed and the increased speed of the motor on starting presently opens it, thus causing the solenoid circuit to become dead. Otherwise the two alternative arrangements, including the use of a centrifugal switch, are equivalents electrically. Furthermore, the presence of a centrifugal switch is not altogether essential to the otherwise dependable functioning of the solenoid in actuating the nozzle adjusting mechanism although it tends to bring about a more positive control of the solenoid.

Having set forth a full and clear embodiment of the invention, I claim:

1. In a suction cleaner, the combination of a motor-driven suction-creating unit including a nozzle, a wheeled frame pivotally connected with said unit, adjusting mechanism for successively lowering said nozzle into contact with the floor covering and automatically elevating the same to a predetermined height above the surface of said floor covering, and means operative by the starting current of the motor to actuate said adjusting mechanism.

2. In a suction cleaner, the combination of a casing provided with a nozzle, a motor-driven suction-creating unit, a wheeled support having a pivotal connection with said casing and permitting the adjustment of said nozzle relative to the surface to be cleaned, and mechanism intermediate said casing and said support and operative to lower the nozzle momentarily into contact with the surface to be cleaned and then to raise it automatically to a predetermined height above said surface, and power-generating means associated with said motor and operative to actuate said mechanism only during the starting of said motor.

3. In a suction cleaner, the combination of a casing provided with a nozzle, a suction fan driven by an electric motor, a wheeled support for said casing pivotally connected therewith for limited vertical adjustment, mechanism intermediate said casing and said wheeled support and operative to successively lower said nozzle into contact with the surface to be cleaned and thence to raise the same automatically to a predetermined height above said surface, said mechanism including a lever, and a solenoid in the motor circuit and operatively connected with said lever for actuating the adjusting mechanism during the starting period only of said motor.

4. In a suction cleaner, the combination of a casing provided with a nozzle and suction creating means, a motor driving said suction creating means, a wheeled support pivotally mounted on the underside of said casing, means for adjusting the height of said nozzle above the carpet surface and comprising mechanism operative to momentarily lower said nozzle into contact with said carpet surface and then to raise it automatically to a predetermined height above the same, said mechanism including a lever pivotally mounted on said wheeled support, and a solenoid mounted on said casing and operatively connected to said lever, said solenoid being electrically connected with said motor whereby the excess starting current delivered to said motor energizes said solenoid to actuate said operating lever during the starting period of said motor only.

5. In a suction cleaner, the combination of a casing provided with a nozzle and suction creating means including a fan, a motor driving said fan, a wheeled support for said casing having pivotal connection with the underside thereof, means for adjusting the height of said nozzle comprising a ratchet lever pivotally mounted on said wheeled support and a lever operated pawl normally engaging said ratchet lever to support said casing, and an operating lever operatively connected with said pawl and shiftable in one direction to disengage said pawl from said ratchet lever to permit said nozzle to drop into contact with the carpet surface, and in the opposite direction to re-engage said pawl with said ratchet lever and thereby raise said nozzle to a predetermined height above the carpet surface through the medium of tension means acting on said operating lever, and a solenoid operatively connected with said lever and electrically connected in the circuit with said motor whereby the solenoid is energized only during the starting period of said motor to actuate said operating lever.
10. In a suction cleaner having a casing provided with a nozzle and a suction creating fan, a motor driving said fan, a wheeled support for said casing having pivotal connection with the underside thereof, means for adjusting the height of said nozzle to the surface of the carpet to be cleaned comprising a ratchet lever pivotally mounted on said wheeled support and having a cam supporting said casing from beneath and an operating lever operatively connected with said ratchet lever, a spring pressed pawl carried by said operating lever and normally engaging said ratchet lever, said lever actuating said pawl in its movement in one direction to release said ratchet sector thereby permitting said nozzle to drop into contact with the carpet surface and in the movement of said operating lever in the opposite direction to permit said pawl to re-engage said ratchet sector and thereby raise said nozzle a predetermined distance above the carpet surface, and a solenoid mounted on said casing and having a core operatively connected with said operating lever, said solenoid being electrically connected in the circuit with said motor whereby the starting current of said motor energizes said solenoid momentarily to actuate said operating lever.
15. In a suction cleaner having a casing, a suction creating fan, a motor for driving said fan, a wheeled carriage pivotally connected to the underside of said casing, mechanism operative to adjust the height of said nozzle with respect to the surface to be cleaned by momentarily lowering the nozzle into contact with the carpet surface and then automatically raising it to a predetermined height above the same, a solenoid in circuit with said motor and operatively connected with said mechanism whereby the current supplied to said motor on starting energizes said solenoid and actuates said mechanism, and a switch in circuit with said solenoid and controlled by the speed of said motor for demagnetizing said solenoid upon said motor reaching a predetermined speed.
20. In a suction cleaner having a casing provided with a nozzle at its forward end and housing a suction creating fan, a motor for driving said fan, a wheeled carriage pivotally connected to the underside of said casing normally supporting the same with said nozzle above the carpet surface, mechanism operative to permit said
25. nozzle to drop momentarily into contact with the carpet surface and then to be automatically raised to a predetermined height above said surface, means for automatically actuating said mechanism comprising a solenoid in circuit with said motor and operatively connected with said mechanism whereby the current supplied to said motor on starting energizes said solenoid momentarily to actuate said mechanism, and a switch in circuit with said solenoid and controlled by the speed of said motor to demagnetize said solenoid upon said motor reaching a predetermined speed.
30. In a suction cleaner having a casing provided with a nozzle at its forward end and housing a suction fan, a motor directly connected with said fan, a carriage pivotally connected to the underside of said casing adjacent its rear end, mechanism intermediate said carriage and said casing for adjusting said nozzle relative to the floor surface being cleaned and comprising a pawl and ratchet mechanism operative to depress said nozzle momentarily into contact with the carpet surface and tension means acting subsequently to elevate said nozzle to a predetermined height above said carpet surface, and means for automatically actuating said pawl and ratchet mechanism comprising an operating lever, a solenoid mounted on said casing and having an endwise shiftable core operatively connected with said operating lever, said solenoid being electrically connected with said motor whereby the current supplied to the latter on starting is available to energize said solenoid and displace said armature to shift said operating lever in one direction, and a centrifugal switch in circuit with said solenoid and carried by the armature shaft of said motor whereby said solenoid is short circuited at a predetermined speed of said motor to allow said operating lever to shift in the opposite direction to complete the nozzle height adjusting operation.
35. In a suction cleaner having a casing provided with a nozzle at its forward end and a fan chamber, a motor driven fan in said fan chamber, a wheeled carriage pivotally connected with the underside of said casing adjacent one end thereof, a ratchet lever carried by said carriage and having a cam supporting said casing adjacent the nozzle end thereof, an operating lever pivotally mounted on said carriage and having a spring pressed pawl normally engaging a toothed sector on said ratchet lever to hold the same against displacement, said operating lever being shiftable in one direction to disengage said pawl from said sector thereby dropping said nozzle into contact with the floor covering, tension means acting to return said operating lever to its normal position whereby said ratchet sector is re-engaged by said pawl to elevate said nozzle to a predetermined height above the surface of the floor covering, a solenoid mounted on the underside of said casing and having an endwise shiftable core operatively connected with said operating lever, said solenoid being electrically connected with said motor whereby the current supplied to said motor is available to energize said solenoid and actuate said operating lever in one direction, and a centrifugal switch in circuit with said solenoid and operatively connected with said motor whereby said solenoid is demagnetized upon the motor reaching a predetermined speed thus permitting said tension means to function to complete the nozzle adjusting operation.
40. In a suction cleaner having a casing provided with a nozzle at its forward end and housing a suction creating fan, a motor for driving said fan, a wheeled carriage pivotally connected to the underside of said casing, mechanism operative to adjust the height of said nozzle with respect to the surface to be cleaned by momentarily lowering the nozzle into contact with the carpet surface and then automatically raising it to a predetermined height above the same, a solenoid in circuit with said motor and operatively connected with said mechanism whereby the current supplied to said motor on starting energizes said solenoid and actuates said mechanism, and a switch in circuit with said solenoid and controlled by the speed of said motor for demagnetizing said solenoid upon said motor reaching a predetermined speed.
45. In a suction cleaner having a casing provided with a nozzle at its forward end and housing a suction creating fan, a motor for driving said fan, a wheeled carriage pivotally connected to the underside of said casing, mechanism operative to adjust the height of said nozzle with respect to the surface to be cleaned by momentarily lowering the nozzle into contact with the carpet surface and then automatically raising it to a predetermined height above the same, a solenoid in circuit with said motor and operatively connected with said mechanism whereby the current supplied to said motor on starting energizes said solenoid and actuates said mechanism, and a switch in circuit with said solenoid and controlled by the speed of said motor for demagnetizing said solenoid upon said motor reaching a predetermined speed.
50. In a suction cleaner having a casing provided with a nozzle at its forward end and housing a suction creating fan, a motor for driving said fan, a wheeled carriage pivotally connected to the underside of said casing, mechanism operative to adjust the height of said nozzle with respect to the surface to be cleaned by momentarily lowering the nozzle into contact with the carpet surface and then automatically raising it to a predetermined height above the same, a solenoid in circuit with said motor and operatively connected with said mechanism whereby the current supplied to said motor on starting energizes said solenoid and actuates said mechanism, and a switch in circuit with said solenoid and controlled by the speed of said motor for demagnetizing said solenoid upon said motor reaching a predetermined speed.
55. In a suction cleaner having a casing provided with a nozzle at its forward end and housing a suction creating fan, a motor for driving said fan, a wheeled carriage pivotally connected to the underside of said casing, mechanism operative to adjust the height of said nozzle with respect to the surface to be cleaned by momentarily lowering the nozzle into contact with the carpet surface and then automatically raising it to a predetermined height above the same, a solenoid in circuit with said motor and operatively connected with said mechanism whereby the current supplied to said motor on starting energizes said solenoid and actuates said mechanism, and a switch in circuit with said solenoid and controlled by the speed of said motor for demagnetizing said solenoid upon said motor reaching a predetermined speed.
60. In a suction cleaner having a casing provided with a nozzle at its forward end and housing a suction creating fan, a motor for driving said fan, a wheeled carriage pivotally connected to the underside of said casing, mechanism operative to adjust the height of said nozzle with respect to the surface to be cleaned by momentarily lowering the nozzle into contact with the carpet surface and then automatically raising it to a predetermined height above the same, a solenoid in circuit with said motor and operatively connected with said mechanism whereby the current supplied to said motor on starting energizes said solenoid and actuates said mechanism, and a switch in circuit with said solenoid and controlled by the speed of said motor for demagnetizing said solenoid upon said motor reaching a predetermined speed.
65. In a suction cleaner having a casing provided with a nozzle at its forward end and housing a suction creating fan, a motor for driving said fan, a wheeled carriage pivotally connected to the underside of said casing, mechanism operative to adjust the height of said nozzle with respect to the surface to be cleaned by momentarily lowering the nozzle into contact with the carpet surface and then automatically raising it to a predetermined height above the same, a solenoid in circuit with said motor and operatively connected with said mechanism whereby the current supplied to said motor on starting energizes said solenoid and actuates said mechanism, and a switch in circuit with said solenoid and controlled by the speed of said motor for demagnetizing said solenoid upon said motor reaching a predetermined speed.
70. In a suction cleaner having a casing provided with a nozzle at its forward end and housing a suction creating fan, a motor for driving said fan, a wheeled carriage pivotally connected to the underside of said casing, mechanism operative to adjust the height of said nozzle with respect to the surface to be cleaned by momentarily lowering the nozzle into contact with the carpet surface and then automatically raising it to a predetermined height above the same, a solenoid in circuit with said motor and operatively connected with said mechanism whereby the current supplied to said motor on starting energizes said solenoid and actuates said mechanism, and a switch in circuit with said solenoid and controlled by the speed of said motor for demagnetizing said solenoid upon said motor reaching a predetermined speed.
